ANIMATED TELEVISION ASH TRAY NOVELTY

Ettie B. Bellett, Venice, Calif., assignor to Donald
Frankel, Beverly Hills, Calif.

Application September 2, 1952, Serial No. 21,287

Term of patent 14 years

(Cl. D85—2)

To all whom it may concern:

Be it known that I, Ettie B. Bellett, a citizen of the United States, residing at Venice, county of Los Angeles, and State of California, have invented a new, original, and ornamental Design for Animated Television Ash Tray Novelty, of which the following is a specification, reference being had to the accompanying drawing, forming a part hereof.

Fig. 1 is a perspective view of an animated television ash tray novelty, showing my new design; and

Fig. 2 is a fragmentary top plan view thereof.

The dominant features of my new design are shown in solid lines. Fig. 1 is lined to indicate transparency. The human figures shown on the screen in Fig. 1 in broken lines are for illus-

trative purposes only. The tray portion is partly broken away in Fig. 2 for convenience of illustration.

I claim:

The ornamental design for an animated television ash tray novelty, as shown and described.

ETTIE B. BELLETT.
